UNITED STATES PATENT OFFICE.

GEORGE W. DOVER, OF PROVIDENCE, RHODE ISLAND, ASSIGNOR TO DOVERCRAFT COMPANY INC., OF PROVIDENCE, RHODE ISLAND, A CORPORATION OF RHODE ISLAND.

CURTAIN-SUPPORTING STRUCTURE.

Application filed December 22, 1925. Serial No. 77,152.

This invention relates to an improved curtain supporting structure adapted to support divided draperies upon opposite sides of a window in such a manner as to be capable of being turned into normal position in front of the window or to be rotated into position away from in front of the window as well as to be removed from normal position whereby the curtains are supported above the window, and replaced in lowered position so as to be held in lowered position during the removal and replacement of curtains.

One object of the invention is to provide a structure of the character described comprising independently movable curtain supports located upon opposite sides of the window, which supports may be each removably held in normal curtain supporting position or moved into and held in lowered position to facilitate removal and replacement of the curtains.

Another object of the invention is the provision of means whereby each of the curtain supporting arms may be readily located in the proper angular position with respect to its shaft and with respect to the remaining curtain supporting arms whereby the straight portions of said arms will be positioned in parallel relation to each other and held in proper position relative to each other and the shaft when the holding means therefor are tightened.

A further object of the invention is to provide an indexing means for adjusting the angular position of the supporting shaft, to compensate for variations in the supporting arms upon opposite sides of the window and permit the proper alignment of the curtain supporting arms upon opposite sides of the window.

Referring to the drawings:—

Fig. 1 is a front elevational view of a window casing showing the position of the curtain supporting structures upon opposite sides thereof.

Fig. 2 is a side elevational view of the structure shown in Fig. 1, the normal raised position of the structure being shown in full lines, and the lowered position of the curtain supporting structure being indicated in dotted lines.

Fig. 3 is a top plan view of the curtain supporting structure upon one side of the window.

Fig. 4 is an enlarged plan view of the lower arm of the bracket member,

Fig. 5 is an enlarged plan view of the lower arm of the lower bracket member showing the indexing mechanism applied thereto, taken along the line 5—5 of Fig. 2.

Fig. 6 is an enlarged plan view of that portion of one of the curtain arms which surrounds the shaft,

Fig. 7 is an enlarged plan view of the upper face of the nut which supports the curtain arms on the shaft,

Fig. 8 is an enlarged plan view of the upper arm of the lower bracket member, and,

Fig. 9 is an enlarged sectional view taken along the line 9—9 of Fig. 1.

In the embodiment of the invention illustrated herewith 1 designates the top portion and 2 the side portions of a window frame of the usual form. The curtain support comprises duplicate structures located adjacent to the side portions 2 of the frame, the elements of the duplicate structures located upon opposite sides of the frame are similar in all respects and the same reference characters will be used to designate corresponding elements of the structures.

Each of the duplicate curtain supporting structures comprises a vertical shaft or rod 3, provided with spaced reduced portions 4 and 5 formed therein for a purpose which will be more fully described hereinafter, and having the upper and lower ends thereof threaded as indicated at 6 and 7. The upper end portion of each shaft 3 is inserted in a bearing opening 8 formed in an upper bracket 9, which may be secured to the top portion 1 of the frame by a screw or other suitable fastening device 10. A lower bracket 12 is provided to assist in supporting the shaft 3 and comprises a portion 13 engaging the side portion 2 of the frame and secured thereto by screws 14 or similar fastening devices. An upper arm 15 projects from the portion 13 of the lower bracket, and a lower arm 16 also projects therefrom, being located directly below the upper bracket. When the shaft 3 is in its normal curtain supporting position as shown in Fig. 1, it is supported by having its upper end portion inserted in the bearing opening 8 in the top bracket and its lower end portion inserted in a bearing opening 17 formed in the lower arm 16 of the lower bracket.

The upper arm 15 of the lower bracket ter-

minates short of the shaft 3 when the shaft is in its normal curtain supporting position as above described.

Curtain arms 19, 20 and 21 are carried by each shaft 3 being secured thereto and located relative to the shaft and each other after the manner now to be described.

A supporting nut 22, which is provided upon its upper face with a definite number of regularly spaced teeth 23, is threaded upon the upper end 6 of the shaft and so positioned that one of the teeth 23 is properly located relative to the shaft. A nut 24 which is threaded on the shaft in advance of the nut 22 is then threaded up into clamping engagement with the nut 22 to clamp the nut 22 securely in position and hold the same against movement. Each of the curtain arms 19, 20 and 21, is provided with a portion 25 bent to surround the shaft 3 which portion is provided upon its opposite sides with teeth 26 adapted to interfit with the teeth 23 of the nut 22 or the teeth of the portion 25 of the next adjacent arm. When the nut 22 is positioned in proper angular relation to the shaft the curtain arms 19, 20 and 21 may be placed thereon so that the teeth 26 on the portions 25 thereof interfit in such a manner that the straight portions 30 of the curtain arms are in substantially exact parallelism with each other and properly positioned angularly with respect to the shaft. The nut 27 is then threaded down into binding engagement with the portion 25 of the curtain arm 21 whereby the curtain arms are secured in position on the shaft 3. The curtain arms 19, 20 and 21 are provided with extensions 28, 29 and 30 respectively which are adapted to slide over the straight portions of the curtain arms and may be adjusted on the arms to regulate the effective length of said arms whereby the arms may be adjusted to fit windows of varying width. Each curtain arm 19 and its extension 28 is adapted to support the usual lace curtain to the center of the window from each side; each curtain 20 and its extension 29 supports the drop curtain on one side of the window; and each curtain arm 21 and its extension 30 supports a divided valance extending from one side of the window to the center thereof.

In applying the structure to a window the upper and lower brackets are secured in place, and, after the curtain arms have been secured to the shafts, the upper end of each shaft is inserted in the bearing opening 8 of the upper bracket and forced upwardly a sufficient distance to enable the lower end of the shaft to be inserted in the bearing opening 17 in the lower arm of the lower bracket. The metal around the bearing opening 8 is forced upwardly to form a flange 31 extending around the bearing opening 8.

The lower arm 16 of the lower bracket is provided with a bent up portion 33 and an indexing member 34 is positioned upon the upper face of the arm 16 being adjustably secured thereto by a bolt 35 passed through a slot 36 in the indexing member and an opening in the bent up portion 33, the bolt being held in adjusted position by a nut 37 fitting within the lower part of the bent up portion 33. The indexing member 34 is provided with a bearing opening 38, adapted to register with the bearing opening 17 in the lower arm 16, and is provided upon its upper face with radiating grooves 39 adapted to receive a pin 46 carried by the shaft 3.

In applying the curtain supporting structure to a window it is desirable that the corresponding curtain arms on opposite sides of the window be in substantially exact alignment when the parts are in operative position as shown in Fig. 1. In order to accomplish this the nut 22 having teeth 23 is carefully adjusted on the shaft and the curtain arms provided with teeth 26 so positioned thereon that the straight portions of the curtain arms may be parallel with the window when the pin 46 is located in the proper groove 39. It may be, however, that the nut 22 will not be positioned angularly of the shaft at the exact point for accomplishing this object, in which case the necessary adjustment may be made by loosening the bolt 35 and turning the indexing member 34 slightly about the shaft 3 to bring the curtain arms on opposite sides of the window into exact alignment. The bolt 35 may then be tightened and the indexing member thus clamped to the lower arm 16 to hold the curtain arms in aligned position.

The upper arm 15 of the lower bracket member is provided with a bearing opening 40 having a narrowed slot 41 communicating therewith; and the lower arm 16 of the lower bracket member is provided with a bearing opening 42, in vertical alignment with the bearing opening 40, and having a narrowed slot 43 communicating therewith. When it is desired to remove curtains from the curtain arms and replace them by others, the shafts 3 may be removed from the positions shown in Fig. 1 by first raising the lower threaded ends 7 from the bearing openings 17 and then withdrawing the threaded portions 6 from the bearing openings 8 of the upper brackets. The reduced portions 4 and 5 of the shafts 4 are then inserted in the slots 41 and 43 to position the shafts in the bearing openings 40 and 42 where they will be supported within easy reach to remove or replace the curtains. The curtain supporting structures may then be placed in the positions shown in Fig. 1 as previously described.

In order to prevent accidental removal of

the curtain supporting structures from the positions shown in Fig. 1, wing-nuts 45 are provided which may be threaded upon the threaded portions 7 of the shafts to prevent the removal of the shafts from the bearing openings 8 and 17 until the nuts 45 have been removed.

It is to be understood that the curtain supporting structures may be readily turned by means of the pin 46 to bring the curtains into position in front of the window or away from in front of the window, the pin 46 engaging with an appropriate groove 39 to hold the structure releasably in either of these positions.

What I claim is:

1. A curtain supporting structure comprising a shaft, curtain arms carried by said shaft, an upper bracket member provided with a bearing opening, a lower bracket member provided with upper and lower arms, the said lower arm being provided with a bearing opening registering with the bearing opening in said upper bracket for supporting the shaft in raised position, said upper and lower arms of said lower bracket member being provided with registering openings off-set from the first named registering bearing openings for supporting said shaft in lowered position.

2. A curtain supporting structure comprising a shaft, curtain supporting arms carried by said shaft, upper and lower bracket members provided with bearing openings for rotatably supporting said shaft in raised position, said lower bracket member being provided with upper and lower arms having registering recesses formed in one edge thereof for supporting said shaft in lowered position.

3. A curtain supporting structure comprising a vertical shaft, curtain arms carried by said shaft, upper and lower brackets provided with bearing openings for rotatably supporting said shaft in raised position, said lower bracket being provided with upper and lower arms having aligned bearing openings for rotatably supporting said shaft in lowered position, and means for preventing the accidental removal of said shaft from the bearing openings in said upper and lower brackets.

4. In a curtain supporting structure, a shaft, curtain arms carried by said shaft, means for securing said arms to said shaft to insure that each of said arms will occupy a predetermined angular position relative to the shaft comprising a nut provided upon one face with radial corrugations, the said arms being provided upon opposite edges

with corrugations whereby the corrugations upon the opposite edges of said arms and one face of said nut interfit to position the arms in the desired angular relation to said shaft, and means for binding said arms into clamping engagement with said nut.

5. In a curtain supporting structure, a shaft, curtain supporting arms provided with portions adapted to fit over said shaft, a stop for said arms carried by said shaft, and interfitting means carried by said stop and the portions of said arms surrounding said shaft whereby the several arms are clamped in a predetermined angular position relative to said shaft.

6. In a curtain supporting structure, a shaft, curtain supporting arms carried by said shaft, upper and lower bracket members rotatably supporting said shaft, and an indexing member carried by said lower bracket for effecting angular adjustment of said shaft.

7. In a curtain supporting structure, a shaft, curtain supporting arms carried by said shaft, upper and lower bracket members rotatably supporting said shaft, an indexing member carried by said lower bracket member and provided with grooves for the reception of a pin carried by the shaft, and means for adjusting said indexing member relative to said lower bracket member to vary the position of said curtain arms in a horizontal direction.

8. In a curtain structure for windows, vertical shafts located upon opposite sides of a window, curtain arms carried by said shafts, and means for adjusting said shafts to bring corresponding arms on opposite sides of the window into alignment.

9. In a curtain supporting structure for windows, vertical shafts located upon opposite sides of a window, bearings for said shafts, curtain arms carried by said shafts, and means associated with certain of said bearings for adjusting said shafts to bring corresponding arms on opposite sides of the window into alignment.

10. In a curtain supporting structure for windows, vertical shafts located upon opposite sides of a window, bearings for said shafts, curtain arms carried by said shafts, means for angularly positioning said curtain arms relative to said shafts, and means associated with certain of said bearings for adjusting said shafts to bring corresponding arms on opposite sides of the window into alignment.

In testimony whereof I have affixed my signature.

GEORGE W. DOVER.
